UNITED STATES PATENT OFFICE.

HERBERT T. HERR, OF PITTSBURGH, PENNSYLVANIA, ASSIGNOR, BY MESNE ASSIGNMENTS, TO THE WESTINGHOUSE MACHINE COMPANY, OF EAST PITTSBURGH, PENNSYLVANIA, A CORPORATION OF PENNSYLVANIA.

MULTIPLE CONTROL.

1,231,257.

Specification of Letters Patent. Patented June 26, 1917.

Application filed May 7, 1913. Serial No. 766,168.

To all whom it may concern:

Be it known that I, HERBERT T. HERR, a citizen of the United States, and a resident of Pittsburgh, in the county of Allegheny and State of Pennsylvania, have made a new and useful Invention in Multiple Control, of which the following is a specification.

This invention relates to a multiple control system in which a manually operated device may control a plurality of mechanisms at a point distant from the controller. One of the objects of the invention is to provide means whereby fluid pressure may be caused to actuate a relay which in turn may cause a motor to operate. Another object is to provide means whereby a plurality of devices may be caused to operate synchronously. Another object of the invention is to provide means whereby the speed of the motor controlled by the relay may be governed. Another object of the invention is to provide means whereby a plurality of motors may be caused to operate in unison and may correspondingly be caused to cease operation. I have shown the invention as being applied in connection with valve operating motors for steam engines, but it is obvious that the system may be employed in connection with other mechanisms.

In the drawings:

Figure 1 is a diagrammatical view of the system constructed in accordance with my invention in which a single-acting valve operating motor is employed;

Fig. 2 is a similar view in which a double-acting valve operating motor is employed;

Fig. 3 is an enlarged sectional view through the controller;

Fig. 4 is a sectional view through a portion of the operating handle for the controller; and

Fig. 5 is a detail view of the operating handle.

Referring now to the drawings by numerals of reference:

10 designates a main reservoir in which air at a predetermined pressure may be stored. The main reservoir 10 communicates with a controller 11 through a pipe 12, and the controller 11 supplies air to a plurality of relays,—in the present instance two, indicated by the reference numerals

13 and 14,—through the pipe 15 and its 55 branches 16 and 17. Each relay is of the single-acting type, for example, the one designated by 14 consisting of a cylinder 18, a piston 19, a spring 20 acting against the piston which is opposed by the pressure delivered through a controller pipe 17 communicating with the cylinder 18. The relays control the delivery of air pressure to the motors 21 and 22, each motor being attached to a valve, as for example, the one 60 designated by the numerals 23 and 24. The motor 22 is approximately the same construction as that designated by the reference numeral 21 and consists of a cylinder 25 having therein a piston 26 between which 65 and one end of the cylinder 22 is a spring 27 which may be opposed by air pressure from the main reservoir. A motor controlling valve 28 on the stem 29 is adapted to slide in a cylinder 30 carried by the 70 relay cylinder 18. The cylinder 30 is in communication with the main reservoir 10 through a pipe 31 and air may be delivered from said cylinder 30 through a pipe 32 to a cylinder 25. The cylinder 30 is also 75 provided with an exhaust port 33 which may be closed by a valve 34 on the stem 29. The stem 29 is connected to the stem of the piston 19 by a lever 35 and the links 36. The lever 35 is also connected to the 80 stem 26' of the piston 26 at 37. The stem 26' also carries the balanced valve 38 in the valve casing 24. The cylinder 30 corresponds to the cylinder 30 and is attached to the motor 13 and it receives air pressure 85 from a branch pipe 31', which is really part of the pipe 31. From the pipe 31' air may pass through the cylinder 30' to a pipe 32' to the motor 21. The operating mechanisms for the relay motor controlling valve 90 and the motor, as well as a connection for the movable element of the valve 23 are like those described for the valve 24, so it is thought that it is not necessary to enter into a detailed description at this time. 100

I shall now proceed to describe in detail the air distributing mechanism which is best illustrated in Figs. 3, 4, and 5:

The air distributing device is illustrated as comprising a casing having a central cylindrical portion 39 divided by a partition or wall 40. This cylindrical portion is provided with removable ends 41 and 42. By

reference to Fig. 3 it will be observed that the partition 40 divides the casing of the distributor into an upper chamber 43 and a lower chamber 44. In the upper chamber 5 is a reciprocatory valve 45 mounted on a hollow stem 46. The valve is adapted to alternately cover and uncover the inlet port 47 and exhaust port 48. When the inlet port 47 is uncovered by the valve, air may 10 enter through said port 47 to the upper chamber 43 and into the chamber 44 through the port 49. There is a piston 50 in the chamber 44 which is normally pressed in one direction by the spring 51, one end of 15 which bears against a piston rod 52 and the other end of which bears against the end 41 of the casing. The piston rod is connected by an articulated joint to an operating handle 53 at 52'. The operating 20 handle is provided with elongated slots 54 in which slide blocks 55 pivoted at 56 to the valve stem 46. The handle 53 is guided in a slotted segmental bar 57 supported on the casing of the distributor 11. The handle 53 may be held in any position along 25 said bar by the friction clutch 58 (see Fig. 5); if desired the segmental bar may be calibrated to guide the operator in determining the position of the handle for any 30 degree of pressure to be maintained in the distributing device.

By reference to Fig. 3 it will be observed that that part of the chamber 44 in rear of the piston 50 is adapted to communicate with the interior of the hollow valve stem 46 through the ports 59 and 60 so that any air which may leak past the piston may be exhausted through the atmospheric exhaust 48 which will at all times be in communication with the interior of the rod 46 35 through the port 61; the air is distributed from the distributing device through a port 62 leading from the chamber 44.

Assuming now that all the parts are properly assembled and suppose it is desired to operate the valve motors in unison so that the valves on the respective engines will be caused to operate both synchronously and so as to open like amounts: The operator 45 may move the handle from left to right so as to uncover the port 47. Air will flow through the chamber 43 into the chamber 44 and pass out through the port 62. In moving the valve 45 the fulcrum for the 50 lever was at 52'. If the valve 45 was moved a sufficient distance to allow say 10 pounds pressure per square inch to accumulate in the pipe 15 and chamber 44, there would be a total pressure in pounds of ten times the 55 area of the piston in inches exerted in opposition to the spring 51 with the result that the spring would be compressed slightly, the piston moving back from right to left and carrying with it the lower end 60 of the lever 53. As the lever 53 in such an

event would be fulcrumed at 58 the valve 45 would be moved from right to left a sufficient distance to close the port 47 and 10 pounds pressure would be maintained in the chamber 44. If any of the air should leak 70 from the chamber 44, the spring would distend and in moving the piston 50 from left to right the valve 45 would be moved with it to uncover the port 47 and admit enough air to again restore the pressure to 10 75 pounds. If additional pressure were desired, the lever 53 would be moved still farther from left to right to uncover the port 47 and a determined additional amount of air would be admitted to the casing of the 80 distributor until the pressure had accumulated enough to again cause the piston and spring to operate the valve to close the port 47. If it were desired to exhaust part of the air, the operator would move the lever 85 53 toward the left so as to uncover the port 48 and establish communication between the chamber 44 and the port 48 to exhaust some 90 of the air. Just as soon as sufficient air is exhausted, the spring 51 would distend carrying with it the piston 50 and the valve 45 to close off communication between the chamber 44 and the port 48 and retain whatever pressure remains.

I shall now proceed to describe briefly the 95 operation of the system according to the mechanisms illustrated in Figs. 1, 3, 4, and 5.

Whatever pressure is admitted through the port 62 to the pipe 15 will be transmitted to the relays 13 and 14. Inasmuch as the 100 springs in these relays tend to move the pistons in one direction, and inasmuch as the springs in their distended positions cause the motor operating valves to close communication between the main reservoir 10 105 and the motor cylinders, it will be apparent that when the air pressure is exerted against the pistons in the relays 13 and 14 said pistons will be moved against the force of the 110 springs, and in view of the fact that the levers 35 are fulcrumed at 37, the motor operating valves will be moved so as to uncover the inlet ports for the pipes 31 and 31' admitting pressure to the pipes 32 and 32' 115 and through them to the cylinders of the motors 21 and 22. Now, the pressures in the motors 21 and 22 will cause compression of the springs back of the pistons, it being understood that these motors are single acting so as to cause a movement in one direction 120 to be imparted to the pistons, with the result that the valves 38 are unseated and the engines which they control may have motive fluid admitted to them. Of course, it is apparent that in place of the valves and 125 valve casings 23 and 24 electrical contacts could be made for operating an electrical controller or any other device could be operated by the motors 21 and 22. The movement of the pistons 26 will be in proportion

to the amount of pressure admitted to the cylinders of said motors, so if 10 pounds pressure is admitted from the air distributor the relay valves will be moved a slight 5 distance against the action of their springs so as to slightly uncover the ports for the pipes 31 and 31', and as soon as enough air is admitted to the motors 21 and 22 to impart a slight movement to their pistons 10 such movement will cause the motor operating valves to close, because when movement is imparted to the piston 26 the fulcrum for the levers 35 changes to the point 35', which is the connection between the lever and the 15 piston for the relay. The amount of movement imparted to the pistons 26 will determine the amount of opening movement imparted to the valve (if a valve be attached to it), so that the amount of fluid passing 20 through the valve casing may be governed. If the air is exhausted from the pipes 17 and 15 back through the chamber 44 and exhaust port 48, the springs 20 will move the pistons 19 in a direction from left to right so as to 25 cause the valve 28 to close off communication between the reservoir and the motor and cause what air had previously been fed to the motor or motors to be exhausted through the port 33. It will be apparent that any 30 number of relays and fluid motors may be controlled by connecting the necessary mechanisms to the pipe 17 and the main reservoir, and that all of these will work simultaneously, and all of them will be under the 35 control of an operator who manipulates the lever 53. I do not desire to limit myself to the form shown in the drawings, nor do I wish it to be understood that the mechanism is adapted for use only for steam engines, it being obvious that the motors 21 40 and 22 may be employed for multiple control system, as for example, for controlling two locomotives when trains are being double-headed, or for controlling the motors in 45 a number of electric cars in an electric train, and for various other purposes.

The mechanism shown in Fig. 2 is very similar to that shown in Fig. 1, the main difference being that in the illustration in 50 Fig. 2, I have shown the motor as being double-acting instead of single-acting. Substantially the same mechanism is employed up to the relay cylinders 18 which are provided with the spring 20, the piston 19, link 55 36, the lever 35 and a motor cylinder 22'. The motor cylinders are provided with valve casings 63 which are in communication with the main reservoir through the pipes 31. These valve casings are provided with the 60 valves 64 connected by link 36' to the lever 35. The motor cylinder 22' is provided near its opposite ends with ports 65 and 66 which may alternately be inlet and exhaust ports, for example, when the valve 64 is moved 65 from right to left, the valve part 67 will un-

cover the port 65 and as air cannot enter the port 66 on account of the valve part 68, air will enter the left end of the piston of the cylinder 22' and move the piston 69 from left to right to impart an opening movement 70 to the valve 38. If air is exhausted from the pipe 17 in the usual way, the spring 20 will move the piston 19 in the relay from left to right; as the lever 35 will then be fulcrumed at 35' the valve 64 will open the port 75 65 to atmosphere and exhaust the air from the left side of the piston 69 and admit air to the right side of the piston 69 through the port 66 so as to impart a closing movement to the valve 38. 80

Variations of the motors, relays and similar mechanisms may be resorted to without departing from the spirit of the invention, the operation of the distributing device and the generic features involved shown in both 85 Figs. 1 and 2 being the same.

Having thus described my invention, what I claim is:

1. In combination with a plurality of valve operating motors, a separate valve for 90 controlling the operation of each motor, a separate relay for controlling the operation of each valve, and pressure controlling means for simultaneously delivering a constant actuating pressure to all the relay devices, and for delivering regulated pressure through the respective valves to all the 95 motors.

2. The combination with a plurality of motors, relays for operating said motors, 100 and a manually adjustable pressure distributing device for admitting determined degrees of fluid pressure to said relays and for maintaining the pressure delivered to said relays constant. 105

3. A plurality of motors, a source of fluid pressure for said motors, an independent valve for each motor, a relay for operating each valve, and a fluid pressure device adapted to synchronously operate all of the 110 relays to simultaneously admit equal quantities of fluid to all of the motors.

4. The combination with valve operating motors, motor controlling valves, relays connected to the motor controlling valves, 115 means for operating the relays simultaneously or synchronously, and means responsive to the motor controlling valves for admitting pressure to the motors.

5. In combination with a plurality of 120 valve operating motors, an independent valve for controlling the operation of each motor, a pressure responsive relay for controlling the operation of each valve, a single distributing device for delivering regulable 125 pressure to all the relay devices, and means for actuating each valve in response to the operation of its corresponding valve operating motor.

6. In combination with a plurality of 130

valve operating motors, an independent valve for controlling the operation of each motor, a pressure responsive relay for controlling the operation of each valve, means between each motor and its controlling valve for actuating the valve in response to movements of the motor, and a pressure distributing device for simultaneously admitting actuating pressure to each relay and for 10 maintaining the actuating pressure constant.

7. In combination with a plurality of motors, a valve for controlling each motor, a pressure actuated plunger for operating

each valve, a manually controlled mechanism for simultaneously distributing adjustable fluid pressure to all of said plungers, and means controlling said mechanism for maintaining the adjusted fluid pressure constant. 15

In testimony whereof, I have hereunto 20 subscribed my name this 3rd day of May, 1913.

HERBERT T. HERR.
